ATTORNEY.

UNITED STATES PATENT OFFICE.

FREDERICK HAMILTON, OF PROVIDENCE, RHODE ISLAND, ASSIGNOR OF ONE-HALF TO FREDERICK A. STEVENS, OF PROVIDENCE, RHODE ISLAND.

LENS-PROTRACTOR.

No. 901,612.

Specification of Letters Patent.

Patented Oct. 20, 1908.

Application filed April 18, 1908. Serial No. 427,793.

To all whom it may concern:

Be it known that I, FREDERICK HAMILTON, a citizen of the United States, residing at Providence, in the county of Providence and 5 State of Rhode Island, have invented certain new and useful Improvements in Lens-Protractors, of which the following is a specification.

My invention relates to protractors adapted for use in decentering, marking and testing lenses; and has for its essential objects means for guiding the operator in securing uniform positioning of the lens with relation to the graduations of the protractor in cases 15 of repeated use; means for facilitating the manual application and control of the lens, means for elevating the graduated surface; means for protecting the latter from chips or grit; and means for increasing, the strength, 20 durability, and convenience of the structure; as well as means for facilitating the accurate measuring of the lens.

To the above ends my invention consists essentially in the novel form, arrangement, 25 construction, and combination of parts hereinafter described, and illustrated in the accompanying drawings, wherein,

Figure 1 is a plan view of my novel protractor. Fig. 2, an end elevation of the 30 same. Fig. 3, a section on line $x-x$ of Fig. 1, and Fig. 4, a bottom plan view of the same.

Like characters of reference indicate like parts throughout the views.

My novel device comprises a plate of sheet 35 metal, A, elliptical or oval in outline and having a curved rounded or convex body portion, a, and a downwardly and inwardly inclined marginal flange, a'. The outer surface of the plate, A, is covered by a sheet of 40 celluloid or other similar material, B, which overlaps the flange, a', and whose margin, b, is folded against the inner surface of the flange. A metallic retaining ring, C, of thin metal is provided, angular in cross section, 45 having a substantially horizontal base portion, c, and an upwardly and outwardly inclined side portion, c'. The outline of the ring corresponds in shape with the margin of the plate, A, but is of slightly less diameter 50 to accommodate the folded portion, b, of the sheet, B, between the outer surfaces of the portion, c', and the flange, a', by which surfaces the fold, b, is frictionally retained in fixed position. Frictionally retained by the 55 inner faces of the ring portions, c and c', is a

thick strip of cardboard, D, which serves as a base or filler for my device.

Printed upon the upper surface of my device are the lens measuring graduations, E, showing in full lines, e; the even degrees, and 60 in broken lines, e', the odd degrees whereby the lines are unusually emphasized. In order that my device may perform the functions of a measure for decentering lenses besides its functions as a mere protractor there 65 are provided along the major and minor axes respectively, of the scale, E, lines of dots, F and G, constituting a millimeter scale.

It will be observed that the elliptical form of my protractor facilitates the use of the 70 thumb and finger to simultaneously engage the upper and lower margin of the protractor and of the lens which is being applied thereto. The smooth curved upper surface insures the absence of dust or grit and is in shape particularly adapted to accommodate a lens. The elevation of the scale above the base enables it to be readily grasped from the bench by the operator. The shape of the device 75 enables the operator to avoid the common error of cutting a cylindrical lens at a wrong axis.

The assemblage of the parts of my structure is simple and inexpensive in practice.

In use it is only necessary to determine the 80 amount of the power of the lens in the direction that it is wished to decenter and after having first marked the true center of the lens, it is laid on the protractor, moved square in, out, up or down, as the case may 85 be, until the optical center is placed at the proper distance from the center of protractor to obtain the necessary prismatic power, then re-dot where the vertical and horizontal lines of the protractor cross. Also dot the 90 extreme edges of the lens on the horizontal or 95 meridian of the protractor. When arranging on the cutting machine place the lens so the three dots will represent the horizontal or 100 meridian, having the central one exactly 105 in the center of the lens when cut.

What I claim is:

1. A convex lens protractor having a substantially elliptical outline, and provided upon its face with graduations.

2. A lens protractor having a substantially elliptical outline and provided upon its face with radial graduations and with lines of dots indicating millimeters arranged along its major and minor axes.

3. In a lens protractor, the combination with a convex elliptical plate, of a smooth material upon the exterior of the plate provided with graduations, and means for supporting the plate. 25
4. In a lens protractor, the combination with a convex elliptical plate, of a flange upon the margin of the plate, a smooth material upon the plate whose margin is folded against the face of the flange, a retaining ring frictionally engaging the marginal fold, and a body strip supported by the ring. 30
5. In a lens protractor, the combination with an elliptical plate, of a flange upon the margin of the plate, a smooth material upon the plate provided with a scale and whose margin is folded against the face of the flange, a retaining ring engaging the marginal fold, and a body strip mounted in the ring. 35
6. In a lens protractor, the combination with a convex elliptical plate provided with a downwardly extending marginal flange, of a sheet of smooth material provided with a graduated scale covering the plate and folded against the inner face of the flange, a ring provided with a horizontal portion and with a vertical portion, which vertical portion rests against the folded portion of the sheet, and a body strip resting upon the horizontal portion of the ring. 40
7. A lens protractor comprising a plate of elliptical form with rounded body portion and downwardly and inwardly inclined marginal flange, a base, a retaining ring engaging said plate and holding said base therein, graduations upon the upper surface extending around the same, and means along the major and minor axes respectively constituting a millimeter scale. 45

In testimony whereof I have affixed my signature in presence of two witnesses.

FREDERICK HAMILTON.
